UNITED STATES PATENT OFFICE.

RICHARD H. CARR AND CORNELIUS B. WATSON, OF COLUMBUS, OHIO, ASSIGNEES TO THE PURE OIL COMPANY, OF CHICAGO, ILLINOIS, A CORPORATION OF OHIO.

LOW-TEMPERATURE DISTILLATION OF BITUMINOUS COAL.

Application filed April 15, 1926. Serial No. 102,332.

This invention relates to the coking of coal under conditions of low temperatures and pressures, and comprises a method of utilizing bituminous coal and like solid fuels for the production of coke and by-products which consists in positively advancing coal in an upward direction through a closed tower or retort, wherein the temperature of the coal is gradually raised until the coal reaches the upper or hottest portion of the tower, the heating of the coal being accomplished, preferably, through the medium of introducing superheated steam or heated oil vapors into the top of the tower and into intimate contact with the coal therein, at which point the coke is removed from the tower, the liberated vapors and other gases, due to distillation, being removed from the coal between its point of introduction and the coke outlet.

It is an object of the present invention to provide a method of distilling bituminous coal by an economical and effective process so as to secure therefrom by-products in the form of hydrocarbon gases and vapors and to obtain from these such commercial products as distillate, lubricating oils, waxes and the like in addition to the coke. Under the action of the superheated steam or oil vapor introduced into the top of the retort and, in opposition to the upwardly moving coal, the vaporization of the volatile content of the coal is effected; these products being removed from the coal at a point between the relatively cool and heated portions of the retort. In order to obtain any large yield of the by-products through distilling coal a careful adjustment of thermal and other conditions must be made. The temperature of the coal should be caused to rise progressively and gradually through ranges up to the working limits of superheated steam or oil vapor. Volatiles will be removed from the point of formation by progressing downwardly and thereby, encountering colder temperatures causing condensation of said volatiles and permitting of their independent removal from the tower.

In what we regard as the preferred embodiment of our invention, we employ a tower or retort having means for introducing the coal

into the bottom thereof, and for positively advancing the coal in an upward direction through the tower toward the maximum temperature zone disposed at or near the top of the tower; subjecting the coal during its travel through the tower to gradually increasing temperatures to extract therefrom the more volatile hydrocarbon products thereof and to raise the temperature of the coal sufficiently to produce the desired grades of coke. In the present invention it is desirable to avoid the cracking or decomposition of the hydrocarbons initially distilled from the coal, and for this reason we find it practical to employ superheated steam in effecting the process of distillation, except under conditions wherein we use the vapor of a distillate containing heavy hydrocarbon fractions as a heating medium for the coal instead of using superheated steam, in which case the heavy fractions are preferably subjected to decomposition to obtain a maximum yield of the lighter fractions.

In the accompanying drawing there is disclosed diagrammatically and in vertical section a form of apparatus for carrying out the present invention.

In this drawing, the numeral 1 designates a tower or retort, comprising an enlarged funnel shaped body in which the coal undergoing process of distillation and coking is maintained, and the lower end of the tower is formed to provide a restricted coal inlet 2. For purposes of illustration, the inlet of the tower is provided with a charging magazine structure 3, consisting of a plurality of conveyors 3' operating in a water filled casing 3", by which the coal is capable of being forced upwardly into and through the tower in a positively actuated, slowly and progressively moving manner, with the gases sealed against loss.

The walls 4 of the tower define a distilling and coking chamber 5 which may be of any suitable capacity holding for example in commercial installations from fifty to one hundred tons of coal, whereas the inlet may be constructed to contain approximately one ton per charge of coal. At the top of the tower there is provided in this instance a coil 6, con-

- nected with an exteriorly arranged steam pipe 7 having a control valve 8 disposed therein. In this form of the invention superheated steam under temperatures of, for example, from 750 to 800 degrees Fahrenheit may be introduced into the tower and preferably at or near the upper end thereof to heat the contents of the chamber 5. It is within the scope of the invention to use the vapors released from heated fractions of high boiling point, and when such oil vapors are used the temperatures necessarily will be somewhat higher than those given herein when superheated steam is utilized.
15. The superheated steam or oil vapor is directly applied to the top of the body of coal contained in the tower and the heat thereof is allowed to permeate through the ascending body of coal in said chamber, so that the 20 temperature of the coal will be gradually and progressively raised. Before the coal is subjected to the highest temperatures the lighter portions of the hydrocarbon gases, vapors and liquids, which may be said to constitute 25 the primary volatiles, are released from the coal and flow downwardly in counter current direction to the ascending column of coal, thereby vaporizing or condensing said volatiles so that the latter may find exit from the 30 tower by way of the tuyère construction 9, or through the water containing inlet of the tower. It will be understood that one or more of the tuyère outlets may be provided between the inlet 2 and the heated zone 10 in 35 the top of the apparatus. These vapors or liquids may be then led to suitable condensing and separating apparatus (not shown) and reduced to various commercial products such as internal combustion engine fuels and 40 lubricants.
- Leading from the top of the tower is a downwardly and angularly extending coke outlet 11, through which the coke falls by gravitation after reaching the zone 10. It 45 will be understood that the rapidity with which the coal passes through the tower and the temperatures to which it is subjected therein control the extraction of the primary volatiles from a quantitative standpoint, and 50 it is the purpose of the present invention to employ low temperatures so that the extraction of the volatiles will not effect the commercial grade of the finally produced coke. The bottom of the outlet 11 terminates in a 55 liquid sealed container 12, which receives and quenches the coke released from the outlet 11, but allows the steam generated during this operation to travel upwardly through said outlet and into the interior of the tower 1, where it is used in the heating of the coal.
- 60 In view of the foregoing it will be seen that the present invention embodies a process of distilling coal unique in the operation of advancing coal in an upward direction 65 through a tower and wherein the temperature

of the coal is gradually raised until coke is formed by the higher temperatures prevailing in the upper part of the tower, the primary volatiles produced during this operation being released from the tower between the point of coal inlet and the point of coke outlet of the tower. Moreover, the quenching of the coke is effected in such manner as to permit the steam released therefrom to enter the tower and heat the materials therein. These features all contribute toward an economically operating system by which the recovery of the primary volatiles is rendered commercially profitable.

While we have referred specifically in both the description and the following claims to a heating medium in the form of superheated steam or oil vapors, it is intended that these expressions shall be construed to cover any gaseous or vaporous heating medium suitable for the purposes of distillation and which is chemically inert with respect to the fuel body.

What is claimed is:

1. The method of producing coke and distillation products from coal by low temperature distillation and without active combustion, which consists in forcing a body of such fuel in an upward direction through a closed receptacle, introducing into the upper part of said receptacle a gaseous heating medium in the form of superheated steam under temperature conditions sufficient to coke the fuel body in the upper portion of said receptacle without combustion, in removing a certain portion of the primary products of distillation from the fuel body at a point between the fuel inlet and coke outlet of the receptacle, said products of distillation being caused to traverse the fuel body in a direction counter-current to the direction of travel of the fuel body prior to the release of the products of distillation from said receptacle, and in separately removing the coke from said receptacle.

2. The method of producing coke and distillation products from coal by low temperature distillation and without active combustion, which consists in forcing a body of such fuel upwardly through a closed receptacle, subjecting the top of the fuel body within said receptacle to a gaseous heating medium in the form of superheated steam to change the composition of the fuel to that of low temperature coke without active combustion on the part of the fuel body, in removing the formed coke from the receptacle, and in withdrawing from the upwardly moving body of fuel within the receptacle the primary distillates at a position below the coke outlet, said distillates being caused to traverse said fuel body in a direction opposed to the direction of movement of said fuel body prior to the release of the distillates from the receptacle.

3. The method of producing coke and dis-

- tillation products from coal by low temperature distillation and without active combustion, which consists in forcing a body of such fuel in an upward direction through a closed receptacle, introducing into the upper part of said receptacle a gaseous heating medium in the form of superheated steam under temperature conditions sufficient to coke the fuel body in the upper portion of said receptacle 5 without combustion, in removing a certain portion of the primary products of distillation from the fuel body at a point below the coke outlet of the receptacle, said products of distillation being caused to transverse the fuel body in a direction counter-current to the direction of travel of the fuel body prior to the release of the products of distillation from said receptacle, and in separately removing the coke from said receptacle, the fuel body at no time during its passage through the receptacle being heated to a temperature in excess of 1000° Fah.
4. The method of producing coke and distillation products from coal by low temperature distillation and without active combustion, which consists in forcing a body of such fuel in an upward direction through a closed receptacle having a coal inlet and a coke outlet, said receptacle being sealed against the escape of internal fluids, introducing a gaseous heating medium chemically inert with respect to the fuel into the receptacle at the top of the fuel body and into direct contact with the fuel body, the heat derived from said heating medium being such as to effect decomposition of the fuel body without combustion to release the primary distillates thereof, in removing the formed coke from the top of said body, and in causing the primary distillates to traverse the fuel body in a direction opposed to the positive advance of the fuel body through the receptacle, said primary distillates being removed from the receptacle at a position below the coke outlet.
5. The method of producing coke and distillation products from coal by low temperature distillation and without active combustion, which consists in forcing a body of such fuel in an upward direction through a closed receptacle having a coal inlet and a coke outlet, said receptacle being sealed against the escape of internal fluids, introducing a gaseous heating medium having the properties of superheated steam into the receptacle at the top of the fuel body and into direct contact with the fuel body, the heat derived from said heating medium being such as to effect decomposition of the fuel body without combustion to release the primary distillates thereof, in removing the formed coke from the top of said body, and in causing the primary distillates to traverse the fuel body in a direction opposed to the positive advance of the fuel body through the receptacle, said primary distillates being removed from the

receptacle at a position below the coke outlet, the fuel body at no time during its passage through the receptacle being heated to a temperature in excess of 1000° Fah.

6. The method of producing coke and distillation products from coal by low temperature distillation and without active combustion, which consists in positively moving a body of such fuel in an upward direction through a closed receptacle having outwardly flaring walls to provide an increase in diameter from the bottom towards the top, introducing a gaseous heating medium into said receptacle at the top of the fuel body to effect decomposition of the fuel body without combustion of the coke and primary distillates, the primary distillates produced by heating the fuel body being caused to travel through the fuel body in a direction opposed to the upward travel of the fuel body, in removing the formed coke from the top of the fuel body and in removing the primary distillates from the fuel body at a point materially below the coke outlet, the flaring side walls of said receptacle serving to maintain the fuel in a disintegrated pervious condition suitable for heat penetration.

7. The method of producing coke and distillation products from coal by low temperature distillation and without active combustion, which consists in introducing the coal into a closed receptacle and advancing the same upwardly through said receptacle, maintaining the top of the coal body within said receptacle in an open pervious condition suitable for heat penetration, introducing a gaseous heating medium into the receptacle at the top of the coal body, the heating medium being maintained under such conditions of temperature and pressure that the same may penetrate into the upwardly moving body of coal to decompose the latter into coke and primary distillates, removing coke from the top of the fuel body and in removing the distillation products at positions materially below the coke outlet, said distillation products being caused to traverse the coal body in counter-current relationship to the direction of movement of said coal body.

8. The method of producing coke and distillation products from coal by low temperature distillation and without active combustion, which consists in introducing the coal into a closed receptacle and advancing the same upwardly through said receptacle, maintaining the top of the coal body within said receptacle in an open pervious condition suitable for heat penetration, introducing a gaseous heating medium into the receptacle at the top of the coal body, the heating medium being maintained under such conditions of temperature pressure that the same may penetrate into the upwardly moving body of coal to decompose the latter into coke and primary distillates, removing

- coke from the top of the fuel body and in removing the distillation products at positions materially below the coke outlet, said distillation products being caused to traverse
- 5 the coal body in counter-current relationship to the direction of movement of said coal body, the fuel body at no time during its

passage through the receptacle being heated to a temperature in excess of 1000° Fah.

In testimony whereof we affix our signatures.
